UNITED STATES PATENT OFFICE.

JOHN LUTSCHAK, OF MILWAUKEE, WISCONSIN.

SHADE ROLLER.

Application filed November 2, 1925. Serial No. 66,214.

This invention relates to improvements in shade rollers. It is the object of the invention to provide a novel and simplified construction whereby a shade roller can be conveniently and economically manufactured of tubular sheet metal and the actuating motor including both the spring and pawls, may be cheaply and simply manufactured and may readily be assembled within the motor and removably fixed therein, whereby to facilitate replacement.

The present invention is particularly concerned with the motor which actuates the shade roller and it is important to an understanding of the invention that attention be paid to the simple, compact and unitary construction of the motor which is such that few parts are required, there is very little mechanism to get out of order, and in the event of spring breakage the entire motor may be unitarily removed and replaced with the utmost facility.

In the drawings:

Figure 1 is a detail view in fragmentary axial section through a shade roller embodying this invention.

Figure 2 is a transverse section taken on the line indicated at 2-2 in Figure 1.

Figure 3 is a view similar to Figure 1, showing a slightly modified form of motor.

Figure 4 is a section taken on line 4-4 of Figure 3.

Figure 5 is a section taken on line 5-5 of Figure 3.

Figure 6 is a detail view in perspective of the end of the spring motor shown in Figure 3.

Like parts are identified by the same reference characters throughout the several views.

The roller per se preferably comprises a tube 10 of sheet metal having caps 11 and 12 for its ends. Cap 11 is provided centrally with a bearing trunnion 13. Cap 12 has a bearing aperture 14 for the motor shaft 15 which has a reduced and squared extremity 16 engageable in a slotted bracket in the usual manner.

The simplicity of the construction, whereby the dogs and other operating parts of the motor are housed within tube 10, is one of the features of the present invention. In each of the devices herein disclosed the inner end of the motor shaft 15 is rotatably guided and positioned against axial thrust by means of an anchorage head designated in

its entirety by reference character 17. In the device shown in Figures 1 and 2, the anchorage head comprises a disk member 18 with which are integrally formed a bearing base 19 and arms 20. Co-operating with arms 20 is the transversely extending plate 21 which also has short arms 22. Arms 20 and 22 have aligned apertures through which extends a transverse pin 23. This pin extends through the walls of tube 10 which are preferably formed with slot recesses or pockets at 24 to receive the head of pin 23 and a nut whereby the pin is secured in place. It will be noted that the shaft 15 is headed at 25 and that the annular flange or head 25 is confined between plate 21 and the cross pin 23. Thus, the shaft is not only provided with bearings at 19 and in plate 21 but, furthermore, due to the location of the annular flange or head 25, the entire shaft 15 is anchored against axial displacement.

Suitably mounted in the anchorage head 17 are a pair of dogs 26 and 27 which engage notches 28 in shaft 15. These dogs operate in the usual manner, being thrown centrifugally out of their seats in notches 28 when the shade 10 is rapidly rotated, and being adapted to engage in such notches when the shade roller is practically at rest. In the present device the dogs or pawls 26 and 27 are pivoted on suitable short pins riveted to disk 18 as shown. Power for the rotation of the shade roller in a direction to wind a shade thereon is furnished by means of the spring 29 which is wound about shaft 15 and stud 19 between the anchorage head and cap 12. The spring is hooked into disk 18 at 29 and is extended through the shaft 15 at 30.

The cap 12 is preferably held merely by friction on the end of tube 10. It will be obvious that when the nut is removed from cross pin 23 to permit the withdrawal of the cross pin it becomes possible to pull shaft 15 and the anchorage head 17 unitarily from the tube which comprises the roller proper. The facility with which the entire motor may be withdrawn and replaced makes it a simple matter to substitute a new motor for one in which the spring has become broken. Furthermore, when the motor is removed from the tube 10, it is very easy to supply a new spring.

In the construction shown in Figures 3 to 6, inclusive, the arrangement is very similar to that already described, with the ex-

ception that the anchorage head 37 in these views is somewhat different from that shown in Figures 1 and 2 at 17. Anchorage head 37 comprises a cup-shaped member having bayonet slots at 38 adapted to receive the anchorage studs 39 which project inwardly from the wall of tube 10. If desired, these studs 39 may be made integrally with the tube by cutting them from the wall thereof in the form of inwardly extending tongues. The length of the anchorage studs is preferably such that they may engage exteriorly on the head or flange 25' carried by shaft 15, thereby preventing axial movement of the shaft in one direction.

The dogs 26 and 27 are pivoted on suitable rivets fixed in the bottom of cup member 37. Preferably the depth of the cup is such that the head or annular flange 25' on shaft 15 will be confined between these dogs or the rivets which carry them on the one hand and the tongues or anchorage studs 39 on the other.

The direction of torque of spring 29 when the motor is wound up is such as to tend to retain the anchorage studs 39 in the innermost portions of the bayonet slots 38, thereby the motor is rigidly anchored as long as the shade roller is in use, but when the torque on spring 29 is relieved the motor can instantly be withdrawn from the casing by rotating it counterclockwise as viewed in Figure 4 and then pulling it axially from the tube.

In both of the above described constructions the entire motor is unitarily removable and is compactly assembled from few parts in such manner that the pawls as well as the spring are housed within the roller tube. It is obvious, therefore, that the invention as disclosed responds fully to the objects of the invention as hereinbefore specified.

I claim:

1. The combination with a hollow shade roller of an anchoring stud extending radially of said roller and disposed within said hollow, a motor housed within said roller and comprising a cup-shaped anchorage head engaged with said stud, a shaft rotatably journaled in and extending from said head, a thrust bearing member secured to

said shaft and confined between said stud and head, pawls carried by and confined within said head, said pawls being engageable with said shaft, and a spring engaging said head and shaft. 55

2. The combination with a hollow shade roller, of an anchoring stud extending radially of said roller and disposed within said hollow, a motor housed within said roller and comprising a cup-shaped anchorage head provided with a bayonet slot engaging said stud, a shaft rotatably journaled in and extending from said head, a thrust bearing member secured to said shaft and head, pawls carried by and confined within said head, said pawls being engageable with said shaft, and a spring engaging said head and shaft. 70

3. The combination with a hollow shade roller, of an anchoring stud extending radially of said roller and disposed within said hollow, a motor housed within said roller and including a cup-shaped anchorage head engaged with said stud, a shaft rotatably journaled in and extending from said head, and a thrust bearing member secured to said shaft and confined between said stud and head. 75

4. The combination with a hollow shade roller, of an anchoring stud extending radially of said roller and disposed within said hollow, a motor housed within said roller and including an anchorage head provided with a portion extending axially of said roller and engaged with said stud, a shaft rotatably journaled in and extending from said head, and a thrust bearing member secured to said shaft and confined between said stud and head. 80

5. The combination with a hollow shade roller, of an anchoring stud extending radially of said roller and disposed within said hollow, a motor housed within said roller and including an anchorage head provided with a portion extending axially of said roller and having a bayonet slot engaging said stud, a shaft rotatably journaled in and extending from said head, and a thrust bearing member secured to said shaft and confined between said stud and head. 95

JOHN LUTSCHAK.
